UNITED STATES PATENT OFFICE.

ERNEST LOUIS HOSPES AND LOUIS NAPOLEON BERGERON, OF STILLWATER, MINNESOTA.

DUMPING-WAGON.

SPECIFICATION forming part of Letters Patent No. 367,103, dated July 26, 1887.

Application filed January 31, 1887. Serial No. 226,074. (No model.)

To all whom it may concern:

Be it known that I, ERNEST LOUIS HOSPES and LOUIS NAPOLEON BERGERON, citizens of the United States, residing in Stillwater, in 5 the county of Washington and State of Minnesota, have invented certain Improvements in Dumping-Wagons; and we do hereby declare that the following is a full and exact description of the same, reference being had to the accompanying drawings, making part of this specification.

Our invention consists in certain improvements in the dumping mechanism of a wagon or cart; in the peculiar means by which the 15 wagon or cart body is held upon the supporting-frame of the running-gear, and in the construction of the tracks on the said supporting-frame, on which the wagon or cart body slides in dumping. These Improvements will 20 be fully set forth and defined in the following description and claims.

In the accompanying drawings, Figure 1 represents a central longitudinal vertical section of a dumping-wagon provided with our 25 improvements; Fig. 2, a top view of the running-gear and frame of the wagon, the wagon-body being removed, except the hinged connection thereof with the endless chain by which the said wagon-body is moved backward and forward in dumping; Fig. 3, a view 30 of the under side of the wagon-body, showing also the endless chains in place in connection therewith; Fig. 4, a rear view of the wagon, the wagon-body being in cross-section in a 35 plane cutting just at the rear of the running-gear frame; Fig. 5, a partial vertical section on an enlarged scale of the wagon around the tilting center of the body, showing the body in a tilting position.

40 Like letters designate corresponding parts in all of the figures.

In the drawings, A represents the wagon-body; B, the frame of the running-gear; C C the front wheels, and D D the hind wheels, of 45 the wagon.

Upon the side timbers, a a, of the supporting-frame B of the wagon two metallic tracks, E E, are secured, on which two counter metallic strips, F F, on the bottom of the wagon-body A respectively slide, to take the wear

and reduce the friction incident to the backward and forward sliding movements of the wagon-body in dumping. There is nothing special in the construction of these parts, except that the steel or iron straps which form 55 the tracks E E are bent around the rear rounded ends, b b, of the side timbers, a a, of the frame, on which rounded parts of the tracks the wagon-body turns and slides a little in tilting; and the said track-straps are ex- 60 tended forward under the said side timbers and embrace the ends c c of the bolster G, which rests on the hind axle, H, of the wagon, and thence forward and upward to the said side timbers, to which they are respectively bolted 65 at d. These track-straps thus fulfill the additional purpose of braces for uniting the bolster to the frame and rendering its connection strong and firm.

For operating the wagon-body, in dumping 70 the same, and returning it to position after its contents shall have been discharged, we employ one or more, preferably two, endless chains, I I, in connection with sprocket-wheels or simple wheels J J on a shaft, K, mounted 75 in the frame B in a proper position forward of the middle line of the wagon-body when in place, for the said chains to pass around at the forward end of their movement, and other sprocket-wheels, L L, on another shaft, M, 80 mounted in the frame near the rear end thereof, for the chains to pass around at the backward end of their movement. The chains are driven either one way or the other by turning either one of the sprocket-wheel shafts, 85 preferably the forward shaft, K, in one or the other direction. This may be effected by extending one end of the shaft beyond the frame and attaching a winch or crank wheel thereto. But in order to gain leverage, so as to move 90 the wagon-body more easily, it is best to gear the shaft K to another parallel shaft, N, mounted in the frame, by the proper gear-wheels, f g, to give the desired relative speeds to the two shafts, and attaching a winch or 95 crank, O, to the shaft N, as shown in the drawings. The endless chains I I are connected with the wagon-body A for imparting the movement thereto by means of shackle-links or swinging hinges P P, pivoted to a cross-bar, 100

h, under the floor of the wagon-body, and also pivoted, respectively, to links of the endless chains, substantially as shown in the drawings. Thus the shackle-links adapt themselves to the proper inclined positions in whichever direction the chains are moving, so as to draw on the wagon-body without strain in either direction. A feature of value in the construction and arrangement of this operating mechanism is that the chains and sprocket-wheels are arranged near the middle of the running-gear frame, one on one side and the other on the other side of the center, whereby the weight thereof is kept from leaning to either side, but is perfectly balanced or equalized on both sides of the wagon. For holding the wagon-body on the supporting frame at all times, whether the body is upright or tilted, and yet not to interfere with the sliding and tilting movements of the body in dumping, we employ two guide-arms or "dogs," *R R*, pivoted upon the rear sprocket-wheel shaft, *M*, and respectively reaching up and holding over the upper sides of longitudinal bars, *j j*, under the bottom of the wagon-body, near the sides thereof. The outwardly-projecting flanges *i i* of the guide-arms are of considerable length, as shown, to rest on the said longitudinal bars of the wagon-body, and thus hold securely upon the said bars without much friction; and the arms turning on the sprocket-shaft *M*, which is concentric with the tilting motion of the wagon-body, hold the said wagon-body on the frame as well when it is tilted as when it is upright. Suitable washers, *k k*, if necessary, are placed on the shaft *M* between the arms *R R* and sprocket-wheels *L L*, to keep them separated and retain the arms in proper position.

45 A suitable hook, *l*, attached to the front part of the frame *B* under the driver's seat *S*, hooking into an eye, *m*, on the front end of the wagon-body, serves to hold the said wagon-body securely in place. Any equivalent means may be employed. 45

We claim as our invention—

1. The tracks *E E*, in combination with the side timbers, *a a*, having rounded rear ends, and the bolster *G*, the said tracks being bent around the rounded rear ends of the said timbers and serving as braces for the bolster, substantially as herein set forth. 50

2. The combination, with the tilting wagon-body *A* and running-gear frame *B*, of the endless chains *I I*, coupled to the wagon-body, sprocket-wheels *J J* and *L L*, and shafts *K M*, substantially as and for the purpose herein specified. 55

3. The combination of the wagon-body *A*, endless chains *I I*, and swinging hinges *P P*, pivoted to the said wagon-body and chains, substantially as and for the purpose herein set forth. 60

4. The pivoted guide-arms *R R*, in combination with the wagon body *A* and sprocket-wheel shaft *M* of the frame *B*, substantially as and for the purpose herein set forth. 65

In testimony whereof we have hereunto set our hands in the presence of two subscribing witnesses.

ERNEST LOUIS HOSPES.
LOUIS NAPOLEON BERGERON.
